UNITED STATES PATENT OFFICE.

CARL THIEME, OF ZEITZ, GERMANY.

FLY-CATCHER.

1,031,889.

Specification of Letters Patent. Patented July 9, 1912.

Application filed April 18, 1911. Serial No. 620,203.

To all whom it may concern:

Be it known that I, CARL THIEME, a citizen of the Empire of Germany, residing at Zeitz, in the Prussian Province of Saxony, 5 Empire of Germany, have invented a new and useful Fly-Catcher, of which the following is a specification.

My invention consists of a box, a cover, a coiled strip coated with paste and fastened 10 with one end at the box and with the other end at the cover, and an elastic disk secured at the lower end of the box. The coated strip can be drawn out like a telescope and 15 the device can then be either hung up or placed on a support. When it is to be suspended, the elastic shallow disk is preferably turned up so as to catch any paste, that may run off the coiled strip. When the fly- 20 catcher is placed on a table, the elastic disk is turned down, so that its edge will bear on the table and thus support the whole device.

I will now proceed to describe my invention with reference to the accompanying drawing, in which—

25 Figure 1 is a vertical longitudinal section through the fly-catcher drawn out and hung up, Fig. 2 is an elevation of the same when placed on some support, and Fig. 3 is an elevation of the fly-catcher when closed.

30 Similar characters of reference refer to similar parts throughout the several views.

The fly-catcher consists of an elastic disk 1, a cylindrical box 2, a coiled strip 3 and a cover 4. All these parts may be made from 35 any suitable material. The disk 1 is secured at the lower end of the box 2 in any desired manner, *e. g.* by means of a flange 5 glued or soldered to the box. The disk is shallow and elastic, so that it can be turned 40 up into the position shown at Fig. 1 or turned down into the position illustrated at Fig. 2. The coiled strip 3 is fastened with its one end in any desired manner on the

inside of the box 2 and with its other end to some part 6 at the inside of the cover 4. 45 The strip is coated with a suitable paste for catching flies. As is shown in Figs. 1 and 2, the coiled strip 3 can be drawn out like a telescope, and it can be pushed into the box 2, which can be closed by the cover 4. 50 Where so preferred, the disk 1 may be connected with the cover 4 by means of a cord 7 or the like, whereby the extension of the coiled strip 3 is limited. The two ends of the cord 7 may be connected with the disk 1 55 and the cover 4 respectively in any desired manner. The cover 4 is provided in its center with a loop 8, by which device can be hung on some peg 9. In case the fly-catcher is thus suspended, the disk 1 is preferably 60 turned up, as shown at Fig. 1, so that it can catch any paste dripping from the coiled strip 3. If the fly-catcher however is placed on some table or support, the disk 1 is first turned down, see Fig. 2, so that its 65 edge will bear on the table and support the whole device.

The fly-catcher can be varied in many respects without departing from the spirit of my invention. The disk 1 may be orna- 70 mented, so as to look like a mushroom or the like.

I claim:

A fly-catcher comprising a box, a cover, an extensible coated strip contained in said box, an elastic saucer-shaped disk fastened to the bottom of said box and formed like the segment of the surface of a sphere so as to be capable of being easily turned up and down along its edge, and a cord connecting the box and cover to limit the extension of the coated strip. 75 80

CARL THIEME.
